HAND SPRAY PUMPS

Alfred P. Smith, Utica, N. Y., assignor to The D. B. Smith & Company, Inc., Utica, N. Y., a corporation of New York

Application November 19, 1952, Serial No. 321,339

2 Claims. (Cl. 299—97)

This invention relates to improvements in hand spray pumps.

The invention is more particularly concerned with hand spray pumps which generally comprise an inner cylinder provided with a nozzle on one end thereof and is also provided with a handle adjacent this nozzle. Such pumps further comprise an outer cylinder telescopably engaged with the inner cylinder and is provided with a hose engageable nut at its outer end.

As is generally known, such pumps operate to force fluid received through the attached hose out through the nozzle upon relative reciprocatory movement of the inner and outer cylinders.

In the use of such pumps, the operator grasps the referred to handle with his left hand and also grasps the outer cylinder with his right hand for the relative reciprocating of the cylinders. The open end of the outer cylinder engages the adjacent end of this handle as a limit of its movement on the inner cylinder in the direction of the nozzle. While such forms of pumps have met with general satisfaction, it has been found that the handle which is of substantial length necessitates a substantially long pump in order to provide a sufficient axial range of reciprocatory movement of the cylinders.

A primary object of the present invention is to provide a pump of the above noted general character but which is of substantially less length with the same axial range of relative reciprocatory movement of the inner and outer cylinders, or which may be of the same length with a substantially greater axial range of reciprocatory movement.

A further object of the invention is to provide a pump of the general character referred to which is adapted for connection thereto of one end of a hose leading from a fluid source beneath the pump whereby the hose will not be subject to twisting.

Other objects and advantages of the invention will become apparent in the course of the following detailed descriptions taken in connection with the accompanying drawings, and wherein:

Fig. 1 is a side elevational view of the pump in collapsed position, the view being on a substantially reduced scale;

Fig. 2 is a partial side elevational view showing the pump fully distended;

Fig. 3 is a view of one end of the pump on full size scale, the view being partially in axial vertical section and partially in side elevation;

Fig. 4 is an end elevation as observed in the plane of line 4—4 on Fig. 3; and

Fig. 5 is a transverse section in the plane of line 5—5 on Fig. 3.

Referring now in detail to the drawings, 10 designates the inner cylinder and 11 designates the outer cylinder.

The inner cylinder 10 has a substantial end portion

2

thereof axially extended through a cylindrical handle 12 which is provided with an outwardly flared open end 13. The opposite end of the cylindrical handle is crimped over a centrally apertured plate 14 through which an externally threaded end portion 15 of the inner cylinder extends.

The inner cylinder is retained against axial movement relative to the handle 12 by means of nuts 16 and 17, the former of which engages the inner face of plate 14 and the latter of which engages the outer face thereof.

As is indicated in Fig. 3 a knurled nut 18 embodied in the nozzle 19 is removably threaded onto the end of the inner cylinder into engagement with the nut 17 through an interposed washer 20.

Details of the nozzle are not herein disclosed since no claim thereto per se is made in this application.

The outer cylinder 11 is as in usual practice provided with a packing nut 21 in its open end for fluid sealing contact with the inner cylinder 10.

The outer cylinder is provided with a hose attaching nut 22 having the axis of its hose engaging portion 23 disposed at right angles to the axes of the cylinders.

As will be noted upon particular reference to Fig. 3, a substantial axial length of the outer cylinder 11 is disposed within the cylindrical handle 12 in the collapsed position of the pump indicated in dot-and-dash lines and in which position the packing nut 21 in the outer cylinder 11 engages the inner nut 16.

With this arrangement the handle provides for movement of the open end of the outer cylinder to substantially the same end of the nozzle on the inner cylinder, whereby a pump of substantially less length than those heretofore in use and having the same axial reciprocatory range is provided.

In the use of the present pump wherein it is convenient to provide the fluid supply in a bucket, a hose may conveniently be attached to the hose engaging portion 23 of the nut 22 and from which it will extend directly to the bucket in the absence of any twisting or kinking of the hose.

While I have disclosed my invention in accordance with a single specific structural embodiment thereof, such is to be considered as illustrative only, and not restrictive, the scope of the invention being defined in the subjoined claims.

What I claim and desire to secure by United States Letters Patent is:

1. In a hand spray pump, an inner cylinder having an externally threaded end portion, an inner nut on said threaded end portion, a circular plate having a central aperture receiving said threaded end portion and with one face of the plate engaged with said nut, an outer nut on said threaded end portion engaged with the other face of said plate, a nozzle structure including a nut on said threaded end portion outwardly of said outer nut, an outer cylinder having an open end telescopically receiving said inner cylinder and having a hose engageable member adjacent its outer end, and a cylindrical handle of greater diameter than said outer cylinder and having open opposite ends, one of said ends being crimped over the peripheral edge of said circular plate, a substantial length of said inner cylinder being enclosed by said cylindrical handle and the latter receiving a substantial length of said outer cylinder in the collapsed position of the inner and outer cylinders.
2. The structure according to claim 1, wherein said open end of said outer cylinder is provided with a packing nut engageable with said inner nut in the collapsed position of the cylinders.
